MULTITURN SPLIT INDUCTOR

Nicholas G. Gagliardi, Brooklyn, Armin A. Finger, New York, and Robert J. Stanton, Brooklyn, N. Y., assignors to Induction Heating Corp., New York, N. Y., a corporation of New York

Application June 27, 1945, Serial No. 601,812

8 Claims. (Cl. 219—47)

1

This invention relates to induction heating apparatus and more particularly to an improved "split" form of inductor or "coil" having a plurality of turns for applying a high frequency field to an object to be heated.

In the induction heating of articles such as crankshafts or other objects which have a neck portion accompanied by enlarged portions at either end of the neck, it is generally necessary to use a "split" type of "coil," that is, one which may be separated for example, substantially along a diameter to afford free access to the space within the inductor for inserting and removing the object to be heated. Heretofore it has been the common practice to heat objects such as crankshafts by using such a split coil having a single turn. In many cases, however, with such a single turn the distribution of the resulting high frequency magnetic flux is such that if the field is applied for a period long enough and is of sufficient intensity to heat the metal within the end portions of the crankpin to the desired depth, then the central portions may become heated to an excessive depth. Accordingly, upon quenching, the middle portion of the crankpin may be hardened to an excessive depth, or if that is avoided by reducing the time and intensity of the heating, then the end portions may be insufficiently heated for proper hardening. As will later be explained in further detail, this undesirable condition may be avoided by using an inductor having two or more turns, whereby the magnetic field and resulting heating may be more uniformly distributed along the crankpin portion to be heated.

However, there are a number of serious problems involved in constructing a practical form of multi-turn inductor, useful for purposes such as heating relatively small crankshafts. That is, the inductor must not only be of the split form capable of being opened up, but at the same time, despite the very limited space available, the convolutions must be formed with large surface areas capable of carrying into the small space the required amount of high frequency current for rapid heating and with avoidance of any excessive or irregular induction effects which would prevent flow of the heavy current uniformly to the desired inductor surfaces. Furthermore, provision must ordinarily be made for conducting cooling fluid through cavities within all of the conductive parts of the inductor. This involves problems due to the confined space available and the necessity of having the inductor of split form and preferably of a form wherein the cooling fluid flow may be continued uninterrupted during the opening and closing of the device for insertion and removal of objects to be heated. Added to these difficulties is that of providing means for rapidly and uniformly applying quenching

2

fluid to the heated surface of the objects being treated.

The present invention provides an inductor construction in which the above noted problems have been satisfactorily overcome in various ways so as to provide a dependable, compact and highly efficient device for the intended purposes.

Various further and more specific objects, features and advantages of the invention will more clearly appear from the detailed description given below taken in connection with the accompanying drawings which form a part of this specification and illustrate merely by way of example, a preferred form of the invention. The invention consists in such novel features, arrangements and combinations of parts as may be shown and described in connection with the apparatus herein disclosed.

In the drawings:

Fig. 1 is a plan view of a preferred form of construction in accordance with the invention;

Fig. 2 is a schematic diagram for illustrating certain principles of operation of inductors of the class herein referred to, and also illustrating certain possible modifications of parts of the device of Fig. 1;

Fig. 3 is a sectional view taken substantially along line 3—3 of Fig. 1;

Fig. 4 is a side elevational view of the device of Fig. 1;

Fig. 5 is an enlarged view of certain details of the device of Fig. 1;

Figs. 6 and 7 are somewhat diagrammatic plan views of an alternative embodiment of the invention;

Fig. 8 is an edge view of such alternative embodiment; and

Fig. 9 is a perspective view showing portions of such embodiment.

Referring now to the drawings in further detail and more particularly to Figs. 1 and 3, the inductor there shown is formed with two "turns," each of which substantially surrounds a central open space 10 adapted to receive an object to be heated, such as the pin portion of a crankshaft. One of these turns, starting at a terminal piece 11, may comprise a sector-like plate 12 extending over an angle of some 90°, a second sector-like plate 13 extending over an angle, for example, of about 180°, and a third sector-like plate 14 extending over an angle of some 90°. The inner edges of these plates outline the space 10 within which the object to be heated is placed. In the particular example shown, this space is cylindrical to accommodate a cylindrical portion to be heated, but of course if the cross section of the object to be heated is of non-circular, or of varying diameter, the inner edges of the plates would be shaped accordingly so that such edges would be brought into close inductive relation with the

surface of the object. The outer or peripheral edges of the plates 12, 13 and 14 may all be recessed as at 15 (Fig. 3) and fixed as by a series of screws 16, to a three-part insulation supporting ring 17, 17', 17'', the parts being separable along a line 18 which is substantially along a diameter of the space 10. Parts 17 and 17'' are separated by the terminal piece 11. When the device is separated along line 18 for insertion or removal of an object to be heated, it will be apparent that the generally semi-circular plate 13 will be carried by insulation piece 17', whereas sector plates 12 and 14 will both remain in place on the part of the insulation structure designated as 17 and 17''.

The second "turn" of the inductor may be also formed of three sector-like plates 12', 13' and 14', located respectively to the rear of the plates 12, 13 and 14 as seen in Fig. 1 and extending in general over corresponding areas (except for connection areas later referred to), and within a plane closely spaced to the rear of the plane of plates 12, 13 and 14 (see Figs. 3-5).

In order to provide for the terminal connections for plates 12' and 14' and for connection means between plates 14 and 12' to complete the two turns, the shapes of plates 12 and 12' are made somewhat different adjacent the terminals, as are also the shapes of plates 14 and 14', as will now be described. As best shown in Figs. 1 and 5, plate 14 may be formed with a triangular protruding area as at 20 adapted to contact with and overlie a triangular insert piece 21 (Fig. 5) which in turn contacts with and overlies a triangular extension 22 formed on plate 12'. If desired of course, the piece 21 might be made integral with one of the plates 14 or 12'. The contacting surfaces of the portions 20, 21 and 22 may be secured together as by pins 23. The plate 12, as shown in Fig. 1, may be formed with a triangular cut-out portion as at 24 to afford clearance for the portions 20 and 21. Also, as shown in Fig. 1, the upper righthand edge portion of the plate 14 may be formed with a cut-out area 25 to afford clearance for that part of the plate 12 which is attached to the terminal piece 11. Similarly, it will be understood that the underneath plate 12' may be formed with a cut-out portion as shown in dotted lines at 25' in Fig. 1, affording clearance for that portion of plate 14' which is attached to a return connection or lug portion 11'. Thus, within an angle of a few degrees within the middle upper portion of the plate assembly, provision is made both for connection of the terminals for the inductor and for connecting one inductor turn to the other, all in a compact arrangement such that despite these connections, the whole structure may have a pancake-like form with relatively large unobstructed areas on the faces of the plates, making it possible to heat objects such as crankshafts of a wide variety of shapes or dimensions while still affording ample clearance. The triangular or wedged shaped form of the connection portions 20, 21 and 22 makes it possible to provide conducting surfaces of considerable size as close as possible to the work piece in aperture 16 for interconnecting the two turns, while still leaving this aperture completely surrounded by inductor surfaces except for a single narrow gap located at the points of the triangular areas. It will be apparent that inductors having more than two turns may be constructed and connected in accordance with the same principles.

As indicated in Fig. 3, insulation structure may

be provided at the rear surface of the periphery of the device, with parts corresponding to the parts 17, 17', etc., as on the front side, one of these parts being indicated at 17a in Fig. 3. Insulation spacer means as at 26 may be secured as by screw means 26' between the peripheries of the front and rear annular insulation structures. The structure is such as to leave an annular space as at 27 surrounding the plate assemblies and communicating with space 28 between the two "turns" of the inductor. From Fig. 3 it is apparent that space 28 opens into the central space 10. As shown in Fig. 1, inlet connections as at 29 and 30 may be provided at two or more points for the annular cavity 27, whereby quenching fluid may be introduced to flow around within the peripheries of the two separable halves of the device and into the space 28 to impinge upon the heated object within space 10. If the device is suspended for use in a vertical plane, then a drip opening as at 31 (Fig. 1) should be provided for allowing the quenching fluid to drain from cavity 27.

The upper half of the device as shown in Fig. 1 may be permanently or semi-permanently attached at its insulation periphery, to a suitable supporting bracket as at 32, the latter in turn being mounted upon an insulation panel 33. The lower half of the device may be detachably clamped to the upper half by quick-detachable clamping means as at 34, 35 (Figs. 1 and 4). Each of these clamping means may comprise a member such as at 36 pivoted as at 37 between a pair of small plates 38 fixed to the insulation structure of the upper half of the device. The member 36 is movable arcuately between a pair of similar small plates 39 fixed to the lower half of the device. The lower end or shank portion of the member 36 may be threaded to receive suitable stop nut means 40. This shank portion may also be surrounded by a spring as at 41 retained within a cylindrical finger piece 42 in a manner such, as will be apparent from the drawings, that one may grasp the piece 42 and pull same downwardly to quickly release the clamping means when it is decided to remove the lower half of the device.

The edges of adjacent sector plates along the line 18 may preferably be spaced slightly except as at 18' at regions close to the object to be heated, thus insuring that especially good contact will be made at these regions where it is important to have the flow of high frequency current as free from irregularities as possible. Pairs of pins as at 43, 44 may be provided in suitable apertures at the edges of the upper and lower sector plates to insure proper alignment of the two halves of the device when placed in position and clamped together.

As above indicated, the electrical connections to the sector plates may include terminal pieces 11 and 11', which may be secured respectively as by brazing, to sector plates 12 and 14'. The members 11 and 11' may be secured also as by brazing to bracket portions 46 and 47 respectively and these in turn may be respectively similarly secured to additional bracket portions 48 and 49 extending back through an aperture 50 in the panel 33 and to suitable terminal portions as at 51, 52 for connection to the source of high frequency current. As best shown in Fig. 1, portions 43 and 49 may be interconnected by an insulation piece 53 which will serve to rigidly retain the bracket portions for the incoming and outgoing circuit connections in the desired closely

spaced relation. The member 53 as attached to the bracket portions may also serve to supplement the connection portions 20, 21 and 22 in rigidly retaining the sector plates of the upper half of the device in proper relative positions. As shown in Fig. 1, the several inductor plates may be formed with apertures for receiving insulation pins 55 passing through the plates from one face of the device to the other, and embraced by spacer washers 56 between the plates 10 of the two "turns," to strengthen the assembly and retain the plates firmly in position.

As shown in Figs. 1, 3 and 4, the various terminal connection portions may be formed with cooling fluid cavities as at 60, 61, and as further shown, cavity 60 for example may communicate with cavities in all of the sector plates for conducting the cooling fluid therethrough in succession and back to the cavity 61. The cavities in plate 12, for example, may include a radially extending cavity portion 62, the outer end of which communicates with the part of the cavity 60 formed in member 11, and the inner end of which communicates with an arcuate cavity 63. The other end of cavity 63 may communicate with another radially extending cavity portion 64 and the outer end of the latter cavity may communicate with a tube 65 extending out through the face of the plate for connection by a flexible hose such as the one shown at 66 (Fig. 4) for conducting the cooling fluid to the cavities in another sector plate. The cavities in all of the plates 12, 12', 14, 14' may be generally similar as will be apparent or readily understood from the dotted lines in Fig. 1. The radial portions of these cavities may be formed by drilling, and such of the openings of the drill holes as are unnecessary in the completed structure, may be stopped by brazing suitable plugs in place. The arcuate portions of these cavities may be initially milled as open grooves, which may be later covered over by arcuate strips as at 63' (see Fig. 3), these arcuate strips being brazed in place. Thus after the cavities are formed with their end portions suitably plugged, except for the desired inlet and outlet, and with the arcuate strips brazed in place, each of the sector plates will present the external appearance of a solid plate with smooth external faces free of any protruding parts which might interfere with proper clearance for the work piece being treated in the device. The cooling fluid cavities in sector plates 13 and 13' may, for example, comprise two arcuate portions as at 70, 71, the cooling fluid entering through a tube 72 and then passing through a radial cavity portion 73 into arcuate cavity portion 70, thence back through arcuate cavity portion 71 into another radial cavity portion 74 to an outlet tube 75.

The inlet and outlet tubes for the cavities of the several sector plates may be connected in series or otherwise in various ways by the hose connections. One suitable arrangement of such hose connection is indicated in Fig. 1, wherein the heavy dot-dash lines indicate hose connections on the front side of the device and the heavy dotted lines indicate the remaining hose connections at the rear face of the device. It will be noted that these flexible connections are such as to permit the cooling fluid to flow in series through the cavities of all the sector plates even when the lower half of the device is unclamped from the upper half during insertion or removal of a work piece.

Reference will now be had to Fig. 2 for explain-

ing the character of results obtainable with a two-turn inductor of this type as contrasted with the results obtainable with a single turn inductor. As shown in this figure, portions *a* and *b* respectively, represent sectional views of two inductor turns made of plate-like form in accordance with the invention. Portions of a crank-shaft are indicated at *c*, the two turns being shown in proper spaced inductive relationship to the crankpin portion. If, with two turns thus arranged, the crankpin portion is subjected to induction heating only for a brief interval, the heat pattern within the crankpin will be in accordance with that shown by the darker cross-hatched areas 80. That is, two separate annular areas adjacent and along the two turns respectively will be heated to a shallow depth. However, upon further heating, these two areas will merge and provide a heat pattern as indicated by the lighter cross-hatched area 81. That is, the metal will be heated to a desirable depth almost uniformly along the length of the crankpin except for the end portions where less heating is ordinarily desired. On the other hand, if an inductor having but a single central turn is used instead of the two-turn inductor shown, then if the end portions of the crankpin are heated to the desired depth, the central portions will be heated too deeply, for example, to an extent indicated by the dotted line 82 in Fig. 2.

In the various figures as shown in full lines in Fig. 2, the internal edges of the turns formed by the inductor plates are shaped to extend parallel to the surface to be heated, viz., as shown, these edges form a cylindrical space concentric with the cylindrical surface of the crankpin. However, in case heat patterns other than that indicated at 81 are desired, the internal edges of the turns may be formed with other shapes. For example, if greater heating at the middle portion of the work piece is desired, then the internal faces of the turns may be shaped as shown by the dotted lines 83. On the other hand, if greater heating is desired at the ends, the internal shape of the inductor portions may be made to conform with the dotted lines 84 for example. In some cases it may be desired to heat one end of the crankpin or other object more than the other. In that event, for example, the aperture within one of the turns may be made larger than the other and as is indicated by the dotted line 85.

Another form of the invention is shown somewhat diagrammatically in Figs. 7-8 inclusive. In this form, instead of using sector plates as at 12 and 14 as of Fig. 1, one may use plates as at 12a and 14a, each of which extends around the central aperture 19 far enough so that the remaining part of the coil "turn" may be filled in by a sector plate 13a, considerably smaller than the plate 13 of Fig. 1.

As indicated in Fig. 8, the second turn may be made up of sector plates as at 12b, 14b, and 13b.

It will be understood that for simplicity of illustration, and to avoid repetition, the insulation supporting structure, as well as the electrical connections and cooling fluid connections, have been omitted in Figs. 6-9, but these may be provided in accordance with the principles disclosed in connection with Figs. 1-4. It will also be understood that the lower portions of the plates 12a, 14a and 12b, 14b which have been cut away in Figs. 6 and 7, may be made in accordance with the construction of the plates 12, 14 and 12', 14',

at the areas where the electrical and fluid connections are applied.

As further indicated in Figs. 6-9, the edges of the sector plates 13a and 13b may be recessed as shown at 70, 71 and 70', 71' to engage complementary recessed edges of the other plates. This makes it possible for the plates 13a, 13b (as held together by any desired insulation structure) to be conveniently slid out of place when, for example, a crank pin is to be inserted in the aperture 10 and then quickly slid into place without the necessity of using any hinge or clamping structure for the plates 13a, 13b. Also since these plates are relatively small and are slidable into good heat-conductive relation with the other plates, it will usually be unnecessary to provide any cooling fluid conduits therethrough, thus eliminating the problems and difficulties of using flexible fluid connections to the removable part of the assembly.

While the invention has been described in detail with respect to a particular preferred example, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A split two-turn inductor for high frequency induction heating, comprising a plurality of generally sector-shaped metal plates arranged in one plane to form a conductor turn for surrounding an object to be heated at a central cavity therein except for a narrow gap between edges of two of the plates, another plurality of generally similar metal plates arranged in an adjacent parallel plane to form a second conductor turn closely spaced from the first and for also surrounding the object to be heated except at a corresponding gap adjacent said first-mentioned gap, means at said gaps for connecting an area at one of said plate edges to an area at an edge of one of said second-named plates, whereby the plates as thus connected form a conductor of two turns for respectively surrounding two parallel bands on the object to be heated, an insulation structure for retaining the plate assemblies in position, said structure being separable into parts, each part carrying plates forming a portion of each conductor turn whereby when such parts are separated, free access may be had to the central cavity for inserting or removing the object to be heated, and means for removably retaining said parts together, the inner edge faces of said plates at said cavity being substantially perpendicular to the planes of said plates.

2. A split two-turn inductor for high frequency induction heating, comprising a plurality of generally sector-shaped metal plates arranged in one plane to form a conductor turn for surrounding an object to be heated at a central cavity therein except for a narrow gap between edges of two of the plates, another plurality of generally similar metal plates arranged in an adjacent parallel plane to form a second conductor turn closely spaced from the first and for also surrounding the object to be heated except at a corresponding gap adjacent said first-mentioned gap, means at said gaps for connecting an area at one of said plate edges to an area at an edge of one of said second-named plates, whereby the plates as thus

connected form a conductor of two turns for respectively surrounding two parallel bands on the object to be heated, an insulation structure for retaining the plate assemblies in position, said structure being separable into parts, each part carrying plates forming a portion of each conductor turn whereby when such parts are separated, free access may be had to the central cavity for inserting or removing the object to be heated, and means for removably retaining said parts together, the inner edges of said plates at said cavity being of cross sections such that they will conform substantially to a convex surface of revolution.

3. A split two-turn inductor for high frequency induction heating, comprising a plurality of generally sector-shaped metal plates arranged in one plane to form a conductor turn for surrounding an object to be heated at a central cavity therein except for a narrow gap between edges of two of the plates, another plurality of generally similar metal plates arranged in an adjacent parallel plane to form a second conductor turn closely spaced from the first and for also surrounding the object to be heated except at a corresponding gap adjacent said first-mentioned gap, means at said gaps for connecting an area at one of said plate edges to an area at an edge of one of said second-named plates, whereby the plates as thus connected form a conductor of two turns for respectively surrounding two parallel bands on the object to be heated, an insulation structure for retaining the plate assemblies in position, said structure being separable into parts, each part carrying plates forming a portion of each conductor turn whereby when such parts are separated, free access may be had to the central cavity for inserting or removing the object to be heated, and means for removably retaining said parts together, the inner edges of said plates at said cavity being of cross sections such that they will conform substantially to a concave surface of revolution.

4. A split two-turn inductor for high frequency induction heating, comprising a plurality of generally sector-shaped metal plates arranged in one plane to form a conductor turn, there being a narrow gap between the edges of two of said plates whereby an object to be heated is surrounded by the conductor turn formed by said plates except for said narrow gap, another plurality of generally similar metal plates arranged in an adjacent parallel plane to form a second conductor turn closely spaced from the first, there being also a narrow gap between the edges of two of the plates forming the second conductor turn, whereby the object to be heated is surrounded except at the corresponding gap adjacent said first mentioned gap, an electric conductor for connecting an area at one of said plate edges of the first named plates to an area at an edge of one of said second named plates, whereby the plates, together with said electric conductor, conjointly form a continuous two-turn inductor consisting of two series connected plate like annularly arranged parallel conductors for surrounding the object to be heated, an insulation structure surrounding the first mentioned plate assembly, an insulation structure surrounding the second mentioned plate assembly, said insulation structures being separable into parts, each part carrying one or more plates forming a portion of its respective conductor turn, mechanism for associating said insulating structures for retaining the plate assemblies in their

desired relative positions closely spaced from one another, said parts, when separated, providing free access to the space within the turn for inserting or removing an object to be heated, and mechanism for detachably clamping together said parts.

5. A split two-turn inductor for high frequency induction heating, comprising a plurality of generally sector-shaped metal plates arranged in one plane to form a conductor turn, there being a narrow gap between the edges of two of the plates whereby said conductor turn is adapted for surrounding an open space except for said narrow gap between the edges of said two plates, and whereby an object in said space is surrounded, except for said narrow gap, another plurality of generally similar metal plates arranged in an adjacent parallel plane to form a second conductor turn closely spaced from the first and having a corresponding gap between two of the plates thereof adjacent said first mentioned gap, whereby the object to be heated is surrounded thereby except for the corresponding gap, an electric conductor mounted at said gaps for connecting an area at one of said plate edges to an area at an edge of one of said second named plates, the plates together with said electric conductors conjointly forming a continuous two-turn conductor for surrounding the object to be heated, an insulation structure surrounding the first mentioned plurality of plates, an insulation structure for surrounding the second mentioned plurality of plates, each of said structures being separable into parts, each part carrying a portion of each conductor turn, free access being provided to the space within said conductor turns upon separation of said parts for inserting or removing an object to be heated, means for detachably clamping said parts together, said plates each being formed with cooling fluid cavities, and flexible insulation conduits for interconnecting said cavities for the flow of cooling fluid therethrough, said insulation structure also being formed with cavities directed toward the space between the two conductor turns, whereby quenching fluid can be directed into the space between the two turns and onto the object being heated.

6. A split two-turn inductor for high frequency induction heating, comprising a plurality of generally sector-shaped metal plates arranged in one plane to form a conductor turn, there being a narrow gap between the edges of two of said plates whereby an open space is surrounded by said plates except for said narrow gap, said open space being adapted to receive an object to be heated, another plurality of generally similar metal plates arranged in an adjacent parallel plane to form a second conductor turn, there being a gap between two of the plates thereof corresponding to the first mentioned gap and adjacent thereto, the second conductor turn thus being adapted for surrounding an open space except for said narrow gap, the latter open space also being adapted to receive said object which is to be heated, an electric conductor directly interconnecting an area at one of said plate edges to an adjacent area at an edge of one of said second named plates, the plates together with said electric conductor conjointly forming a continuous two-turn inductor for surrounding the object to be heated, an insulation structure for each of said conductor turns, mechanism for interconnecting said insulation structures for holding the first and second turns closely spaced and substantially parallel to one another, each insulation structure being separable

5 into parts, each part having connected thereto a substantial portion of each conductor turn, a separation of said insulation structure parts affording free access to the space within the turns for inserting or removing an object, and mechanism for detachably clamping said parts together.

7. In a multturn inductor for high frequency induction heating, the combination comprising a plurality of closely spaced substantially parallel conductor turns, each turn being constituted by a plate-like structure having a central aperture for receiving a workpiece, there being a narrow gap extending substantially radially from the aperture in each plate-like structure, the workpiece being surrounded by each conductor turn, except for its respective narrow gap, means for electrically connecting adjacent conductor turns in the region of the gaps comprising substantially wedge-shaped conductor portions, each comprising a part of the inductor structure, the narrow portions of the wedge-shaped conductor portions being directed toward said aperture, said wedge-shaped portions being substantially co-axial and collectively extending in a direction normal to the planes of the plate-like structures.

8. A split two-turn inductor for high frequency induction heating, comprising an assembly of plate-like conductor elements conjointly forming a disc-like structure arranged in one plane to form a conductor turn, there being a narrow gap between the edges of two of said plate-like conductor elements whereby an object to be heated is surrounded by the conductor turn formed by said plates, except for said narrow gap, another assembly of plate-like conductor elements conjointly forming a disc-like structure arranged in one plane to form another conductor turn there being a narrow gap between the edges of two of the plate-like conductor elements thereof whereby the object to be heated also is surrounded by said other conductor turn except for the narrow gap therein, the second conductor turn being mounted in an adjacent parallel plane closely spaced from the first conductor turn, an electric conductor for connecting an area adjacent one of said gaps upon one plate assembly to an area adjacent the gap upon the other plate assembly whereby the plate assembly together with said electric conductor conjointly form a continuous two-turn conductor for surrounding the object to be heated, each of said plate assemblies having a slidible tongue with groove-retaining means along its sides whereby such piece may be removed and reinserted to permit insertion or removal, in generally radial directions, of workpieces.
